UNITED STATES PATENT OFFICE.

KEIKICHI FUKUYAMA, OF LOS ANGELES, CALIFORNIA.

HEAT APPLICATOR AND ELECTRODE.

Application filed May 9, 1925, Serial No. 29,184. Renewed January 6, 1927.

This invention relates to means for use in combining massage treatment, the application of electric currents for therapeutic effects, the application of heat, the application of moisture, conjointly with the application of any preferred medicated substance, and its objects are to provide a thermo-electric massage device, which will be neat and attractive in appearance, simple in construction, durable and efficient in use, and comparatively inexpensive to manufacture.

A further object is to provide a massage device which is easy to refill and in which the parts may be readily removed and replaced, particularly the contact pad whereby the same may be renewed or replaced for sanitary purposes.

A further object is to provide a massage device embodying electrical elements, a fluid container associated therewith, heat retaining elements encasing the container, and a contact pad adapted for distributing the liquid from the container conjointly with the application of electric current.

In the accompanying drawings, there is shown a preferred embodiment of the invention, it being understood that the drawings do not define the limits of my invention, and that changes may be made in the construction and operation without departing from the spirit of the invention or scope of the claims.

In the drawings:

Figure 1 is a transverse sectional view of a thermo-electric device constructed in accordance with my invention. Fig. 2 is a side elevation of the same. Fig. 3 is a transverse sectional view on line X³—X³ of Fig. 1. Fig. 4 is a sectional detail view of the retaining cap for the bottom of the container.

In carrying out the present invention, there is provided a tubular container 11, which forms the body portion of the electrode. The container 11 is covered with a tubular heat-insulating jacket 12, preferably of paper fabric, which is covered by an exterior jacket 13, preferably of rubber fabric. The top of the container, for refilling purposes, is provided with a cork or plug 14, preferably of rubber, inserted in the opening 15, through which liquids and various temperature regulating agents may be introduced. An inner concentric member 17, fixed to the bottom of the container, projects upwardly with its upper end 18, terminating

in an elongated and very narrow slit 19, through which a liquid may percolate to the interior of the inner member 17. Within the inner member 17, I place a cloth fabric bag 20, containing a medicated powder 21, or other similar therapeutic agent.

The contact element 26, consists preferably of asbestos or felt fabric, and is retained in position on the end of the electrode, by the rubber jacket 13. A wick 22, extends through a central aperture 23, in the retaining cap 24, which forms the bottom of the inner member 17. The wick becomes permeated with the liquid content within the member 17, and allows the same to permeate the contact pad 26.

While but one electrode is shown, it is to be understood that in use, two similar electrodes will be employed, connected to electrical conductors of opposite polarity. In use, the electrodes are first preferably filled with warm or hot water, the bag containing a powder or medicated agent is placed in the inner chamber, and the contact pad is then secured in position, and the device is employed in the usual manner.

Each electrode is provided with an electric wire binding post 25, for connection with respective electrically charged wire terminals 85 (not shown). The retaining cap 24 is frictionally held or retained in position to close the bottom of the inner chamber.

The implement may of course be employed without connection with electric wire terminals. It is not intended to limit the invention to the use of water, but other liquid contents may be employed, or the implement may be used with water of different temperatures for each electrode.

With the use of the present device, the application of the electric current may be uniform and continuous, for the contact pads are constantly moist. The body of the electrode is of sufficient capacity to hold a quantity of fluid, and, if such fluid be heated, is capable of retaining a uniform temperature for some time.

From the foregoing description and drawings, it may be seen that I have provided a simple and efficient apparatus and device for application of the electric current, conjointly with the application of heat, and the application of massage treatment.

What is claimed is:

1. In an electro-therapeutic device, the combination with a tubular body including

- a terminal binding post, a central and axial inner chamber integral with the body and terminating at its upper extremity in a narrow slit, and an opening at the upper end of the body, of a plug forming a closure for the upper opening, a liquid content within the body, a cloth fabric bag within the central inner chamber, a medicated powder within the bag, a cap having a central perforation and inserted in the bottom of the inner chamber, a fabric contact pad mounted on the end of the body, annular members jacketing the body and holding the contact pad in position, and a wick mounted in the perforation in the cap and forming a permeable communicating means between the inner chamber and the contact pad.
2. An electro-therapeutic device, including a tubular body adapted to hold a liquid content, a felt fabric pad detachably mounted on the end of the body, heat-insulating jackets mounted on the body and serving to retain the contact pad in position, an inner chamber concentric and integral with the

body and having a percolating aperture in its upper extremity, a medicated bag within the inner chamber, and a permeable liquid-transmitting element interposed between the inner chamber and the contact pad.

3. The combination with a tubular body and an inner chamber extending axially in the body and having its upper end formed with a percolating slit, said body having an upper refilling hole, and said inner chamber having a lower refilling hole, of a plug forming a closure for the upper refilling hole, a cap forming the closure for the lower refilling hole, and having a central aperture, a wick inserted in said aperture, heat-insulating jackets mounted on the body, a contact pad on the lower end of the body and in contact with said wick, a liquid content within the body, and a medicated filling disposed in the inner chamber.

In testimony whereof, I hereunto affix my signature.

KEIKICHI FUKUYAMA.
